UNITED STATES PATENT OFFICE.

VICTOR R. BROWNING AND EARL H. BROWNING, OF CLEVELAND, OHIO.

LOCOMOTIVE-CRANE.

No. 889,174.

Specification of Letters Patent. Patented May 26, 1908.

Original application filed January 27, 1905, Serial No. 242,849. Divided and this application filed April 27, 1907.
Serial No. 370,580.

To all whom it may concern:

Be it known that we, VICTOR R. BROWNING and EARL H. BROWNING, residing at Cleveland, in the county of Cuyahoga and State of Ohio, have invented a certain new and useful Improvement in Locomotive-Cranes, of which the following is a full, clear, and exact description, reference being had to the accompanying drawings.

10 Our invention relates to locomotive cranes such as shown in our application No. 242,849, filed January 27, 1905, whereof this application is a division and has for its object to provide improved means for operating the various mechanisms of the crane; more specifically, it has for its object the provision of means whereby the levers, clutches, and other mechanism for operating the hoisting and traveling mechanism may be conveniently and quickly assembled and introduced in such assembled condition into the crane and may, when desired, be quickly disassembled.

15

20

Generally speaking, the invention may be defined as consisting of the combinations of elements embodied in the claims hereto annexed.

Referring to the drawings, Figure 1 represents a central vertical sectional view of the 30 gears, drums, shafting, clutches and some of the operating levers for a crane constructed in accordance with our invention; Fig. 2 represents an elevation of the levers, brackets and housings, some of the shaftings, and the 35 engines and operating mechanism being shown in dotted lines; Fig. 3 represents a sectional view taken through the housings just forward of the engine shaft, the lever brackets being shown in elevation and the operating levers being removed for clearness of illustration; Fig. 4 represents a side elevation of the frame which carries the clutch-operating shafts, a portion of the adjacent bracket and the brake lever and a portion of the brake 40 being shown in dotted lines; Fig. 5 represents a side elevation of one of the lever brackets; and Fig. 6 represents a plan view of the frame illustrated in Fig. 3.

Describing the parts by reference numbers, 1 represents the floor frame of the 50 crane, said frame being provided with the depending integral hubs or sleeves 2 and 3, the former being provided for the reception of the journal 4 of the shaft 5, the lower end of which 55 carries the pinion 6 by which the floor frame

and the parts supported thereby may be rotated. The upper end of shaft 5 is provided with the bevel gear 7 meshing with the bevel pinion 8 on a horizontal shaft 9 which is driven from the main or engine shaft 10 through the bevel gears 11 and 12. The hub or sleeve 3 supports a journal 13 for a vertical shaft 14 by which the crane is driven along the track. The upper end of this shaft is provided with a bevel gear 15 meshing with a bevel gear 16 on the counter-shaft 17. The shaft 17 is driven from the shaft 10 by means of the gears 18 and 19 on said shafts respectively and the clutch 20.

21 denotes a counter-shaft which is driven 70 from the shaft 17 by means of gears 22 and 18 on said shafts respectively. Shaft 21 is provided with a bevel gear 23 and clutch 24, by means of which and the bevel gear 25 the motion of the shaft 21 may be transmitted 75 to the vertical shaft 26. Shaft 26 is provided with a worm 27 engaging a worm gear 28 on shaft 29 which carries the drum 30 for hoisting and lowering the crane boom.

31 designates the hoisting drum mounted 80 on a shaft 32 which is operated from the shaft 17 through the reduction gears 33 and 34 and clutch 35.

The details of the means for driving and 85 rotating the crane need no further description here, the same being shown, described and claimed in our application 242,849, hereinbefore referred to.

Bolted to the floor proper of the frame 1, adjacent each edge of the same, are the housings 36. These housings support the engine shaft and most of the horizontal counter-shafts by which the various mechanism of the crane are operated. Extending between 90 these housings, near the upper front portions thereof, is the hollow frame or separator 37. This frame or separator is secured in place by bolts 37^a. The engine shaft 10, counter-shaft 17, and shafts 29 and 32 are supported in bearings formed in housings 36, 95 100 as fully set forth in our application No. 242,849.

38 denotes triangular brackets, which are secured to the frame or separator 37 in line with the brackets 39, integral with and depending from the frame or separator 37. The horizontal counter-shaft 21 is journaled in the rear sides of the lower ends of brackets 39, being held in place by removable caps 39^a (see Fig. 1). The worm wheel 28 and the 110

portion of the drum corresponding to and adjacent to the said wheel are inclosed by means of an integral extension 40 of the frame or separator and a removable casing 41 which completes the inclosure of said gear and the corresponding portion of the drum. The brake band 42 is provided for the drum 31 and has one end connected to a rod 43 extending upwardly and diagonally through 10 the separator or frame, with its upper end projecting through a sleeve 44 thereon and provided with adjusting nuts 45. The opposite end of the brake band is connected to a sleeve 46 journaled on the shaft 47 which 15 is supported by and between bearings in the lower end of one of the brackets 38 and a bearing in the adjacent housing 36. This sleeve is also provided with the hand lever 48 and the foot lever 49, whereby the brake 20 may be applied by hand or foot power, or both.

In order to operate the drum brake and the clutches, we employ a system of levers 48, 49, 50, 51, 52 and 53. For shifting the 25 steam valve links, we employ the levers 54 and 55, said levers being employed for starting and reversing the engine by hand. All 30 of these levers but the two first mentioned, 48 and 49, are provided with sleeves by 35 which they are pivoted to the shaft 56 extending through and supported by the bearings 57, near the lower ends of the brackets 38. These brackets, as will appear more particularly in Figs. 1 and 5, are substantially triangular, having a vertical leg 58, an upper horizontal leg 59, and an inclined leg 60. At each end of the upper horizontal leg 59 is provided an opening 61, 62, respectively. These openings are for the reception 40 of rods 63 and 64 respectively between which extend and upon which are secured the quadrants 65, 66, 67, 68, 69, and 70 for the levers 48 and 50-54 inclusive. Depending from the rod 64 and sleeved thereon is a bracket 45 71 for the shaft 72 which operates the pinch collar 73 for the worm shaft 26. The sleeve of the lever 50 is provided with suitable projecting lugs 74 for the attachment of a link 75 by means of which the bell crank 76 and 50 the clutch of the rotating shaft are operated. Similar lugs are provided for the lever 51 which operates the boom-hoist clutch, for the lever 52 which operates the main hoist clutch, and for the lever 53 which operates 55 the traveling shaft clutch. The lugs with which levers 50 and 52 are connected project rearwardly from their respective sleeves or hubs while the lugs with which levers 51 and 53 are connected project forwardly from their 60 respective sleeves or hubs. The purpose of this construction is that the parts connected to the lugs may not be too close together but have proper clearance both for the proper working of the device and for ease of assembling and access to parts to make necessary 65

repairs. The lugs on the sleeves or hubs of levers 51, 52 and 53 are respectively connected by the links 77, 78 and 79 with the bell crank levers 80, 81, and 82 which operate their respective clutches. The lower end of lever 48 is connected to sleeve 46 on the short shaft 47 which is supported by a bearing in the housing 36 and the lower end of the adjacent bracket 38. Each of the brackets 38 (see Fig. 5) is provided with bolt 75 holes 83, extending through the vertical leg thereof, by means of which said brackets (with all of the levers but 48 assembled therewith) may be bolted or otherwise suitably secured to the frame or separator 70. After the parts have been so assembled, the lever 48 may be passed through its quadrant 80 and bolted to its sleeve on shaft 47.

Immediately below the brackets is the skeleton frame 86. This frame carries the various clutch-operating members which are connected to the links 75, 77, 78, and 79. It is preferably rectangular in outline, and is provided with openings 87, 88, and 89 formed between the sides and ends and the integral cross members 90 and 91. The rear and sides of said frame are each provided with an integral depending skirt 92. The front end of the frame is the cross member 93, which is bolted to the front end of the sides of the frame and is provided with a depending bracket 84. Similar brackets 94 and 95 are carried by the members 90 and 91 respectively. The shaft 96 of the bell crank lever 80 by means of which the boom hoisting clutch collar 97 is operated is pivoted in the upper part of the bracket 84 and in the flange 98 of the member 91. The shaft 99 of the bell crank lever 82 which operates the clutch collar 100 for the traveling shaft of the crane 100 is journaled in the lower ends of the brackets 84 and 95, the latter bracket depending from the flange 98. The shaft 101 of the lever 76 which operates the clutch collar 102 for the rotating shaft of the crane is journaled in 105 brackets 103, 104, bearings being formed in said brackets for the purpose (see Figs. 1, 2 and 5). Adjacent to the side of said frame and journaled in bearings in the brackets 94 and 106 is the shaft 107 for the clutch collar 110 115 and 108 for the main hoisting shaft.

The frame 86 is secured in place by bolts 109 extending through holes 110 (see Figs. 2 and 6) in horizontal flanges near the forward end of the sides of the frame and into the 120 brackets 39 projecting downwardly from the separator as well as by bolts 111 extending through the vertical end flange or skirt of the angle iron 112 at the adjacent portion of the platform 113.

We claim:

1. In a crane or similar device, the combination of brackets, levers operatively supported between said brackets, a frame extending transversely across said crane, and

means for securing said brackets and levers, in an assembled condition, to said frame, substantially as specified.

2. In a crane or similar device, the combination of side housings, a frame extending transversely between said housings, levers for operating the various mechanisms of the crane, brackets between which said levers are mounted, and means for securing said brackets and levers, in an assembled condition, to said frame, substantially as specified.

3. In a crane or similar device, the combination of side housings, shafting within said housings, a pair of brackets having a shaft supported therebetween, operating levers pivotally mounted on said shaft, and means for securing said brackets and levers, in an assembled condition, within said housings, substantially as specified.

4. In a crane or similar device, the combination of a supporting frame, a pair of brackets having a shaft supported therebetween, operating levers pivotally mounted on said shaft, and means for securing said brackets and levers to said supporting frame, substantially as specified.

5. In a crane or similar device, the combination of a main shaft and countershafts, clutches for operating said countershafts from the main shaft, a frame having openings therein, clutch-operating levers pivotally supported in said frame and having each an operating arm, said frame with its clutch-operating levers being removably fitted within the crane, a lever for operating each of said clutch-operating levers, and links extending into said opening and connecting the last mentioned levers within the arms of the clutch-operating levers, substantially as specified.

6. In a crane or similar device, the combination of a main shaft and a countershaft, a clutch for operating said countershaft from the main shaft, a frame having an opening therein, a clutch-operating lever pivotally supported in said frame and having an operating arm, said frame with its clutch-operating lever being removably fitted within the crane, a lever for operating said clutch-operating lever, and a link extending into said opening and connecting the last-mentioned lever with the arm of the clutch-operating lever, substantially as specified.

7. In a crane or similar device, the combination of a main shaft and countershafts, clutches for operating said countershafts from said main shaft, a frame having a plurality of openings therein, clutch-operating levers having shafts extending across said openings, an operating arm for each of said levers, levers pivoted above said frame, and links extending from the last mentioned levers through the openings in the frame and connected with the arms of the clutch-operating levers, substantially as specified.

8. In a crane or similar device, the combination of a main shaft and countershafts, clutches for operating said countershafts from said main shaft, a frame having a pair of openings therein, a clutch-operating lever for each of said openings and having a shaft extending across each of said openings, an operating arm for each of said levers located in an opening, levers pivoted above said frame, and links extending from the last-mentioned levers through the openings in the frame and connected with the arms of the clutch-operating levers, substantially as specified.

9. In a crane or similar device, the combination of housings, a frame extending across said crane between said housings, brackets secured to said frame, levers supported between said brackets, a skeleton frame removably secured to the former frame, clutch-operating levers pivoted in the latter frame, and links connecting the first mentioned levers and the clutch-operating levers, substantially as specified.

10. In a crane or similar device the combination of a main shaft and countershafts, side housings for the crane, a frame extending between said housings operating levers supported from said frame, a frame detachably connected to the former frame, clutch-operating levers pivoted in the latter frame, and links connecting the former levers with the latter levers, substantially as specified.

11. In a crane or similar device the combination of a main shaft and countershafts, a platform and side housings for the crane, a frame extending between said housings, operating levers supported from said frame, a skeleton frame detachably connected to said platform and to the former frame, clutch-operating levers pivoted in the latter frame, and links connecting the former levers with the latter levers, substantially as specified.

12. In a crane or similar device, the combination of a main shaft and countershafts, clutches for operating said countershafts from said main shaft, a frame extending transversely of said crane and having depending brackets, a second frame, clutch-operating levers pivoted in the latter frame, means for securing the last-mentioned frame to the brackets, levers supported from the former frame for operating the clutch-operating levers, and links connecting the former levers with the latter levers, substantially as specified.

13. In a crane or similar device, the combination of a main shaft and countershafts, clutches for operating said countershafts from said main shaft, side-housings, a frame or separator extending between said side housings and having depending brackets, a skeleton frame, clutch-operating levers pivoted in the latter frame, means for removably securing the last-mentioned frame to the

- brackets, levers supported from the former frame for operating the clutch-operating levers, and links connecting the former levers with the latter levers, substantially as specified.
14. In a crane or similar device, the combination of a main shaft and countershafts, side housings, a frame within said housings, clutches for operating the countershafts from the main shaft, a frame having therein clutch-operating levers and detachably connected to the former frame, levers supported from the former frame, and links connecting the latter levers with the former levers.
15. 15. In a crane or similar device, the combination of a main shaft and countershafts, side housings, a frame within said housings, clutches for operating the countershafts from the main shaft, a frame having therein clutch-operating levers and detachably connected to the former frame, levers supported from the former frame, and links connecting the latter levers with the former levers and removably supported from the former frame, substantially as specified.
16. In a crane or similar device, the combination of a main shaft and countershafts, clutches for operating the countershafts from the main shaft, a frame comprising sides and ends and one or more cross members, a clutch-operating lever having its shaft journaled between a cross member and one of the end members, a second clutch-operating lever having its shaft journaled on the opposite side of the cross member from the first-mentioned lever, means for detachably securing said frame in place in the crane, levers for operating the first-mentioned levers, and links connecting the first-mentioned and last-mentioned levers, substantially as specified.
17. In a crane or similar device, the combination of a main shaft and countershafts, clutches for operating the countershafts from the main shaft, a frame detachably secured to said crane and having sides and ends, one of said ends being removable and having a depending bracket, a second bracket carried by said frame, a clutch-operating lever having a shaft pivoted in said brackets, a lever for operating the latter lever, and a link connecting said levers, substantially as specified.
18. In a crane or similar device, the combination of a main shaft and countershafts, clutches for operating the countershafts from the main shaft, a frame removably fitted in said crane, said frame having sides and ends, one of said ends being removable and having bearings formed therein, a cross member uniting the sides of said frame and having bearings therein, clutch-operating levers having their shafts pivoted in said bearings, levers for operating the former levers, and links connecting the former and latter levers, substantially as specified.
19. In a crane or similar device, the combination of a main shaft and countershafts, clutches for operating the countershafts from the main shaft, a frame removably fitted in said crane, said frame having sides and ends, one of said ends having bearings formed therein, a cross member uniting the sides of said frame and having bearings therein, clutch-operating levers having their shafts pivoted in said bearings, levers for operating the former levers, and links connecting the former and latter levers, substantially as specified.
20. In a crane or similar device, the combination of a main shaft and countershafts, clutches for operating the countershafts from the main shaft, means for operating said clutches, said means comprising a pair of triangular brackets, a frame on which said brackets are detachably mounted, rods connecting the upper corners of said brackets, a rod or shaft connecting the lower portions of said brackets, quadrants extending between said rods, and operating levers co-acting with said quadrants and having their lower ends pivoted on the rod or shaft carried by the lower portions of the brackets.
21. In a crane or similar device, the combination of main shaft and countershafts and clutches for operating the latter shafts from the former shaft, of a skeleton frame having sides and ends and a cross member, clutch-operating levers having their shafts pivoted in said frame on opposite sides of said cross member, a shaft or rod supported above said frame and above said cross-member, levers sleeved onto said rod or shaft, some of said levers having lugs projecting rearwardly therefrom and others having lugs projecting forwardly therefrom, and links extending downwardly from said lugs and connecting the same with said clutch-operating levers, substantially as specified.
22. In a crane or similar device the combination of a main shaft and countershafts, clutches for operating said countershafts from said main shaft, levers for operating said clutches, and a pair of brackets having means for supporting said levers, said brackets and the levers and supporting means being adapted to be assembled outside the crane and to be secured in place therein in assembled condition, substantially as specified.
23. In a crane or similar device, the combination of a main shaft and countershafts, clutches for operating said countershafts, levers for operating said clutches, quadrants for said levers, a pair of brackets having means for supporting said levers, said brackets, quadrants and levers being adapted to be assembled outside of the crane and to be secured in place therein in an assembled condition, substantially as specified.
24. In a crane or similar device, the com-

5 combination of a main and a countershaft, a clutch for operating said countershaft from said main shaft, a frame having supports thereon, a clutch-operating device pivoted between said supports, said frame and said device being adapted to be assembled and to be inserted after assembling into the crane, substantially as specified.

10 25. In a crane or similar device, the combination of a main shaft and countershafts, clutches for operating said countershafts from said main shaft, a frame having supports or brackets carried thereby, clutch-operating devices pivoted between said supports or brackets, said frame and the clutch-operating devices being adapted to be assembled and to be inserted, after assembling, into the crane, substantially as specified.

15 26. In a crane or similar device, the combination of a main shaft, a countershaft, a clutch for operating said countershaft from said main shaft, a skeleton frame having a bracket depending from an edge thereof and a bracket depending from an intermediate portion thereof, a clutch-operating device pivoted between the said brackets, and means for detachably securing said frame in place in said crane, substantially as specified.

20 30 35 40 27. In a crane or similar device, the combination of a main and a countershaft, a clutch for operating said countershaft from said main shaft, a skeleton frame having a bracket depending from an edge thereof, a bracket depending from an intermediate portion thereof, and a clutch-operating device pivoted between the brackets, said frame and said clutch-operating device being adapted to be assembled and to be inserted, in such assembled condition, into the crane, substantially as specified.

25 35 45 50 55 28. In a crane or similar device, the combination of a main shaft and a countershaft, a clutch for operating said countershaft from said main shaft, a frame having an opening therein and brackets depending from opposite sides of said opening, a clutch-operating device pivoted between said brackets, an operating lever for said device, and a link extending from said lever into said opening and connected to said device, said frame and clutch-operating device being adapted to be assembled and inserted, in such assembled condition, into said crane, substantially as specified.

55 29. In a crane or similar device, the com-

60 bination of a main shaft and countershafts, clutches for operating said countershafts from said main shaft, a skeleton frame having therein a plurality of openings and depending members on opposite sides of said openings, clutch-operating devices pivoted between said members, levers for operating said devices, and links extending into said openings and connected with the levers of said devices, substantially as specified. .65

65 70 75 30. In a crane or similar device, the combination of a main shaft and countershafts, clutches for operating said countershafts from said main shaft, a skeleton frame having therein a plurality of openings and depending members on opposite sides of said openings, clutch-operating devices pivoted between said members, levers for operating said devices, and links extending into said openings and connecting said levers and said devices, the frame and the clutch-operating devices being adapted to be assembled and inserted, in such assembled condition, into the crane, substantially as specified.

80 31. In a crane or similar device, the combination of a main shaft and countershafts, clutches for said countershafts, brackets, operating levers carried by said brackets, a frame adjacent said brackets and having openings therein, clutch-operating devices 85 extending across said openings, and links connecting said levers and said clutch-operating devices, substantially as specified.

85 90 95 32. In a crane or similar device, the combination of a main shaft and countershafts, 90 clutches for the countershafts, brackets, operating levers and quadrants carried by said brackets, a frame adjacent said brackets having openings therein, clutch-operating devices extending across said openings, and 95 links connecting said levers and devices, the parts being so arranged that the brackets with their levers and quadrants and the frame with its clutch-operating devices may be assembled and inserted, in such assembled condition, into the crane, substantially as specified.

100 In testimony whereof, we hereunto affix our signatures in the presence of two witnesses.

VICTOR R. BROWNING.
EARL H. BROWNING.
